(57) **CLAIM**

The ornamental design for a recording and reproducing device, as shown and described.

DESCRIPTION

FIG. 1 is a perspective view of the front, top and right sides of a recording and reproducing device according to an embodiment of the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating the unclaimed portions of a recording and reproducing device and form no part of the claimed design.

1 Claim, 5 Drawing Sheets

FIG. 1

FIG. 2

FIG. 3

FIG. 4

FIG. 5

FIG. 7
